LOUIS N. D. WILLIAMS, OF OGONTZ, PENNSYLVANIA, ASSIGNOR TO SCOTT & WILLIAMS, INCORPORATED, OF CAMDEN, NEW JERSEY, A CORPORATION OF NEW JERSEY.

KNITTING-MACHINE NEEDLE.

1,114,420.

Specification of Letters Patent. Patented Oct. 20, 1914.

Application filed December 18, 1911. Serial No. 666,582.

To all whom it may concern:

Be it known that I, LOUIS N. D. WILLIAMS, a citizen of the United States, residing in Ogontz, Montgomery county, Pennsylvania, have invented certain Improvements in Knitting-Machine Needles, of which the following is a specification.

My invention relates to swinging needles of the type employed in knitting machines such as that shown in the patent of Robert W. Scott, No. 834,763 dated October 30, 1906, the object of my invention being to provide the swinging shank of the needle with a pivot member which will be securely confined to said shank and will bear an accurate relation to the hooked and latched needle stem at one end of the shank as well as to the opposite end of the shank which is acted upon by the needle actuating cams. This object I attain in the manner hereinafter set forth, reference being had to the accompanying drawings, in which—

Figures 1 and 2 are side views representing needles having pivot members constructed in accordance with my invention; Fig. 3 is an enlarged side view of the pivot portion of the needle shown in Fig. 1, illustrating the first step in the production of the same; Fig. 4 is a transverse section of the same on the line *a—a*, Fig. 3; Fig. 5 is a section similar to Fig. 4 but illustrating the method of completing the pivot member; Fig. 6 is a side view on an enlarged scale of the pivot portion of the needle shown in Fig. 2, illustrating the first step in the production of the same; Fig. 7 is a transverse section of the same on the line *b—b*, Fig. 6; Fig. 8 is a sectional view illustrating the method of completing said pivot member; Fig. 9 is a sectional view illustrating a modified form of pivot member, and Fig. 10 is a view of the jig in which the needle is held during the completion of the pivot member.

In Fig. 1 of the drawing, 1 represents the shank of the needle having at one end the hooked and latched needle stem 2, and having the other end, which is acted upon by the needle operating cams, bent as at 3, although this is not absolutely necessary. The pivot member of the needle shown in Fig. 1 consists of a cupped washer 4 across the cupped face of which is laid the needle shank 1, the flange 5 of the washer being notched or recessed, as at 6, for the recep-

tion of said shank, and being also, by preference, provided with other notches, as at 7, the notches being preferably undercut or having their sides flared laterally from the rim to the base of the flange. The washer 60 also has, by preference, an opening 8 therein, this opening being crossed by the shank of the needle, as shown in Fig. 3. The pivot member is completed by a casting 9 of relatively soft and freely flowing metal, which 65 fills the cup of the washer, and also the notches or recesses 6 and 7 in the flange of the washer and the opening 8 in the body of the same, whereby the casting is firmly locked to the washer. The needle shank is 70 also firmly locked to the casting; longitudinal movement of the shank in respect to the casting being prevented by engagement of the latter with notches 10 in the front and back of the shank, or other suitable means. 75 In order to form the casting 9 the cupped washer, with the needle shank in place therein, is confined between the parts 11 and 12 of a divided mold such as shown in Fig. 5, which mold forms part of a jig, having 80 pins 13 or other suitable means for accurately positioning the ends of the needle in respect to the mold, as shown in Fig. 10. The metal is forced under pressure into the matrix of the mold in a manner similar to 85 that adopted in casting type, the gate 14 being afterward removed from the casting.

The pivot member of the needle shown in Fig. 2 consists of a flat annular or ring washer 15 having two parts, each of which 90 has offsets 17, the shank 1 being clamped between these offset portions of the washer and the member being completed by the casting 18 which fills the central opening of the washer, envelops that portion of the needle 95 shank which crosses said opening and also overlaps the washer on each side, as shown in Fig. 8, the casting operation being performed in the same manner as in producing the casting 9. In a pivot member of this 100 construction the needle shank will be secured against movement in any direction independent of the washer as effectively as in the construction shown in Figs. 1 to 4, and as the pivot member is formed upon each 105 needle shank while the latter is rigidly held in a suitable jig, the pivot members of all the needles must necessarily be uniform and bear an accurate relation to the hooked and latched stem of the needle. The pivot mem- 110

ber shown in Fig. 9, is similar to that shown in Fig. 8, except that it has a single washer 19 instead of the two-part washer 15.

The washers may be constructed of steel, 5 so that the flange 5 of the washer 4 or the peripheral portion of the washer 15 or 19 will constitute a proper bearing for the pivot member of the needles in that part of the machine which carries the same.

10 In the production of the casting which envelopes the needle a metallic alloy might be used which would be hard enough to constitute a bearing surface for the pivot member, in which case the washer might be dispensed 15 with, but the use of the latter is to be preferred.

I claim:

1. A knitting machine needle having a pivot member with a casting which engages 20 and retains the shank of the needle, the latter projecting in both directions from the periphery of the casting.

2. A knitting machine needle having a pivot member comprising a washer, and a 25 casting engaging said washer and engaging and retaining the shank of the needle.

3. A knitting machine needle having a pivot member comprising a washer, and a casting which engages and retains the shank 30 of the needle, occupies an opening in the washer, and laps a portion of said washer.

4. A knitting machine needle having a pivot member comprising a washer, and a casting which engages and retains the shank of the needle, occupies an opening in the washer 35 and overlaps the latter on each side.

5. A knitting machine needle having a pivot member with a casting which envelops the shank of the needle, said shank projecting in both directions from the periphery 40 of the casting.

6. A knitting machine needle having a pivot member comprising a washer, and a casting engaging said washer and enveloping 45 the shank of the needle.

7. A knitting machine needle having a pivot member comprising a washer and a casting which envelopes the shank of the needle, occupies an opening in the washer, 50 and laps a portion of said washer.

8. A knitting machine needle having a pivot member comprising a washer, and a casting which envelopes the shank of the needle, occupies an opening in the washer and overlaps the latter on each side. 55

In testimony whereof, I have signed my name to this specification, in the presence of two subscribing witnesses.

LOUIS N. D. WILLIAMS.
